CLAIM

The ornamental design for a projector, as shown and described.

DESCRIPTION

FIG. 1 is a perspective view of a projector with a lens cover and lens cover control being illustrated in an open position showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective thereof, with the lens cover and the lens cover control shown in a closed position.

The portions of the projector in broken lines are shown for illustrative purposes only and form no part of the claimed design.
